[57] CLAIM

The ornamental design for a large bag with long handle, as shown.

DESCRIPTION

FIG. 1 is a front elevational view of a large bag with long handle, showing my new design, the long handle being omitted for ease of illustration;

FIG. 2 is a top view thereof;

FIG. 3 is a bottom view thereof;

FIG. 4 is a rear view thereof;

FIG. 5 is a right side view thereof;

FIG. 6 is a left side view thereof;

FIG. 7 is a perspective view thereof; and,

FIG. 8 is a perspective view of the complete large bag with long handle.
